Claims priority, application Netherlands July 17, 1959
2 Claims. (Cl. 315—3.5)

This invention relates to travelling-wave tubes in which the electron beam is in interaction with a helical conductor having its ends secured to disc-shaped or annular conductors which are directed at right angles to the axis of the tube and which close the apertures of the wave-guides to which the tube is coupled.

Structures of the above-mentioned kind are already known. In such structures the coupling between the helix and the hollow wave-guide is not wholly sufficient. The annular conductor sometimes has an axially-directed portion to which the helical conductor is connected. However, this involves the disadvantage that the electron beam extends over part of its path in an asymmetric potential field, which gives rise to heating of the conductors due to striking electrons and to charging of ceramic supports present in the surroundings.

Similar difficulties as mentioned above likewise occur if the end of the helical conductor has a portion extending in an axial direction.

An object of the invention is to provide a structure which affords advantages with respect to known tubes.

According to the invention, in a travelling-wave tube in which the electron beam is in interaction with a helical conductor having its ends connected to disc-shaped or annular conductors directed at right angles to the axis of the tube, conductors are provided, one at each end of the helical conductor, which extend substantially parallel to the axis of the helical conductor at same distance outside it and which are connected, on the one hand, to the disc-shaped or annular conductor to which the helical conductor is connected and, on the other hand, to a point remote several turns from the end of the helical conductor.

In a structure according to the invention, it is achieved that the electron beam extends throughout its length in a symmetrical potential field so that electrons are not unnecessarily lost from the beam and charging of ceramic supports in the surroundings does not occur, whilst also proper matching of the helix to the wave-guides to be connected to the tube may readily be achieved.

A structure is already known in which, as reckoned from the end of the helical conductor, a straight conductor extends towards an annular conductor positioned more towards the centre of the tube, but in this case the helical conductor does not extend to the vicinity of the conductors closing the wave-guides to which the tube is connected.

A structure is also known in which a conductor extends through the insulating wall of the tube, at a point located several turns from the end, at right angles to the helix and terminates in a wave-guide. In this case also, the helical conductor does not extend far enough at its ends.

In order that the invention may be readily carried into

2

effect, one embodiment thereof will now be explained in detail, by way of example, with reference to the accompanying diagrammatic drawing, in which:

FIG. 1 shows a longitudinal section of a travelling-wave tube according to the invention,

FIG. 2 shows a cross-section in the direction of arrows II—II in FIG. 1; and

FIG. 3 is a cross section in the direction of the arrows III—III in FIG. 1.

10 In FIG. 1, reference numeral 1 indicates the glass wall of the travelling-wave tube which is provided with two lead-through discs 2 and 3. Secured to the disc 2 by means of a cylindrical transition piece 4 is a helical conductor 5 which is supported by three ceramic rods 6 provided with a number of cuts corresponding to the pitch of the helix. The helical conductor is surrounded by mica plates 8 and 21 which are covered with damping material 9 and 22, respectively, and which are at right angles to the plane of the drawing near the cathode half of the helix and parallel to the drawing near the output half of the helix. The plates 8 (FIG. 2) and plates 21 (FIG. 3) are supported in mica discs 10 positioned at right angles to the axis of the tube and held together by means of two ceramic rods 11. The plates 8 and plates 21 are supported in the direction of their length by means of mica plates 12 and 23, respectively.

20 Provided in the lead-through disc 3 is a transition piece 13 to which the other end of the helical conductor 5 is secured.

25 At each end of the helical conductor there is provided a conductor 14 connected to the transition piece and to a point about three turns from the end.

30 A glass portion 15 contains an electron gun 16 and an accelerating electrode 17. A glass cylinder 18 insulates a collecting electrode 19 from lead-through disc 3. The heat produced in collecting electrode 19 is dissipated by natural cooling of cooling fins 20.

35 What is claimed is:

40 1. An electron discharge device comprising an evacuated envelope, means within said envelope to produce a beam of electrons, a collector electrode in the path of the beam of electrons, a helical conductor between the electron beam producing means and the collector electrode and surrounding the electron beam, an annular conductor transverse to the path of the electron beam between each of the ends of said helical conductor and beam producing means and the collector electrode respectively to which the ends of said helical conductor are connected, and conductor means positioned parallel 45 to the path of the electron beam connecting each of said annular conductors to said helical conductor several turns remote from each end thereof.

45 2. A travelling-wave tube as claimed in claim 1 in which the helical conductor is arranged between two sets of parallel plates which are covered with damping material, said sets of parallel plates being at right angles to each other in the two halves of the tube.
